UNITED STATES PATENT OFFICE

2,098,366

LEVELING MACHINE

Erastus E. Winkley, Lynn, Mass., assignor to
 United Shoe Machinery Corporation, Paterson,
 N. J., a corporation of New Jersey

Application July 7, 1936, Serial No. 89,365

9 Claims. (Cl. 12—34)

This invention relates to machines for applying pressure to the bottoms of shoes, and is herein illustrated as embodied in a leveling machine of the type disclosed in Letters Patent of the United States No. 1,667,761, granted on May 1, 1928, upon an application of E. E. Winkley and H. A. Davenport, and in various Letters Patent therein referred to, although it is to be understood that in its more general aspects the invention is not thus limited in its applicability.

Machines of the above mentioned type comprise in their organization a leveling tool, such as a roll, a shoe support or jack which is adjustable to accommodate shoes of different sizes, and automatic means for imparting to the shoe support swinging movements in directions lengthwise of the shoe the extents of which are determined by the size adjustment of the support to cause the leveling roll to operate along the bottom of the shoe in a predetermined cycle. Such machines are also provided with automatic means for pressing the roll upon the shoe and for relieving the pressure at predetermined times in the cycle of operations of the machine to avoid excessive pressure at the ball of the shoe and for imparting to the leveling roll tipping movements of different extents laterally of the shoe to cause the pressure of the roll to be applied to the shoe at different inclinations when the roll is operating along the forepart and shank portions respectively so that these different portions will be properly leveled.

The present invention provides an improved construction such that in operating upon shoes of different styles, that is, shoes that differ in respect to the relative lengths of their forepart and shank portions, the relative positions of the shoe support and leveling roll are more precisely determined than heretofore each time in the movement of the shoe support when the pressure of the roll is relieved. Such accurate control of the relative positions of the shoe support and leveling roll renders the machine particularly well adapted for use in operating on shoes characterized by a pronounced line or ridge extending across the sole at the ball of the shoe. The construction herein shown is such that for the purpose in view the rate of movement of the shoe support may be adjustably varied when the roll is traversing both the forepart and shank portions of the shoe bottom, so that in operating on a shoe of any style the relief of pressure of the roll will occur each time in the swinging movement of the shoe support when the roll is in a definitely predetermined relation to the ball line of the shoe. In operating on shoes of the character above mentioned this

obviates any danger that there may be of the pressure of the roll obliterating such a line or ridge on the sole. Moreover, since the roll is tipped at one inclination to the shoe bottom when operating along the forepart and at one or more different inclinations to the shoe bottom when operating along the shank, the inclination of the roll being changed at the time of pressure relief, assurance also is afforded that the pressure of the roll will be properly applied to all portions of the forepart and shank. It will be evident that the rate of movement of the shoe support may be thus varied without varying the entire extent of swinging movement imparted to the shoe support to cause the leveling roll to traverse both the forepart and shank which may be controlled as heretofore in accordance with the size adjustment of the jack.

The above and other features of the invention including various novel details of construction and combinations of parts will now be more particularly described by reference to the accompanying drawings and pointed out in the claims.

In the drawings,

Fig. 1 is a view in side elevation of a machine of the type disclosed in the prior Letters Patent hereinbefore mentioned, with the present invention embodied therein;

Fig. 2 is a view in rear elevation of the machine shown in Fig. 1;

Fig. 3 is a section on the line III—III of Fig. 1;

Fig. 4 is a detail view of the cams for operating the mechanism for varying the rate of movement of the shoe support;

Fig. 5 is a plan view of the bottom of a shoe and illustrating diagrammatically the number and extent of relative swinging movements of the shoe support and leveling roll in operating on the bottom of the shoe; and

Fig. 6 is a diagram illustrating the relative timing of the cams which operate different parts of the machine.

Since the invention is illustrated as applied to a leveling machine of a well-known type only such parts of the machine as it is necessary to refer to for an understanding of the invention are shown and will be described in detail. It will be understood that the machine includes in its organization two sets of operating instrumentalities for operating on different shoes in different locations in the machine and that each set comprises an automatically controlled leveling roll 10 and a shoe support or jack which, in the power operation of the machine, is moved automatically in directions lengthwise of the shoe to cause the roll to operate progressively along the bottom of

the shoe. Each jack (Fig. 1) comprises a toe post 12 and a heel post 14 which are pivoted together at 16 for relative adjustment for shoes of different sizes by means of a threaded adjusting rod 18 which moves the heel post toward or from the toe post so that the toe ends of shoes of different sizes will be presented substantially in the same relation to the roll 10. The jack as a whole is operatively movable about the axis of a shaft 20, on which the toe post is mounted, to carry the shoe forwardly and rearwardly under the leveling roll. In these respects the construction shown is similar to that disclosed in Letters Patent of the United States No. 1,239,664, granted on September 11, 1917, upon an application of W. C. Baxter.

Each roll 10 is mounted in a holder 22 fast to the end of a shaft 23 (Fig. 2) which extends through a tubular roll carrier 24 pivotally mounted at 25 (Fig. 1) on the frame of the machine for 20 swinging movements in a vertical plane to press the roll 10 upon the shoe and to relieve the pressure at different respective times in the operation of the machine. To cause the roll to operate along the bottom of the shoe the jack is swung 25 about the axis of the shaft 20 by power-operated mechanism comprising a path cam 26 formed in one face of a cam wheel 28 on a cam shaft 30 and connections from the cam 26 to the jack which will presently be described. Generally speaking, 30 the cycle of operations comprises first a movement of the jack to cause the roll to traverse the shoe from the toe end to the heel seat, then a plurality of backward and forward movements while the roll is operating in the shank, there- 35 after a movement to cause the roll to return to the toe end along one side and then to traverse the shoe from the toe to the heel seat along the opposite side followed by a plurality of backward and forward movements to cause the roll to operate 40 in the shank at that side and, finally, a movement to cause the roll to return to the toe and to leave the shoe. As the roll is thus operating upon the opposite sides of the forepart and shank portions of the shoe, tipping movements of different 45 extents are imparted to the roll to cause the pressure of the roll to be applied to the forepart and shank portions respectively at different inclinations properly to level them.

The shafts 23 are rocked in the roll carriers 24 50 to impart to the leveling rolls their tipping movements by mechanism which is substantially the same as that disclosed in Letters Patent No. 889,287, granted June 2, 1908, upon an application of mine. Fast to the rear ends of the shafts 23 substantially in vertical alinement with the axis 25 of the roll carriers are segments 32 (Fig. 2) 55 engaging rack bars 34 which are connected together by a pinion (not shown) for equal movements in opposite directions. Connected to one 60 of the rack bars 34 is a link 36 pivotally connected to a block 38 slidably mounted in a curved slot 40 formed in a crank arm 42 fast to a shaft 44 to which there is secured an arm 46 connected by a link 48 to a lever 50 (Fig. 2) pivotally 65 mounted on the frame of the machine and carrying a cam roll 52 engaging a path cam 54 formed in the opposite side face of the cam wheel 28. The shape of the cam 54 is such that tipping movements of different extents are imparted to 70 the leveling roll in operating upon the forepart and shank portions respectively of the shoe bottom. For varying the extent of tipping movement imparted to the leveling roll as the different portions of the shoe bottom are acted upon 75 successively by the roll there is provided, as more

fully shown and described in the above-mentioned Letters Patent No. 889,287, four wing cams 56 (Fig. 2) which are controlled from the front of the machine by suitable adjusting mechanism and are operated by a set of fly cams (not shown) on the cam shaft 30. The wing cams 56 engage a roll 58 supported by the downwardly extending arms 60 of a bell-crank lever having a substantially horizontal arm 62 connected by a universal joint to the right-hand end of the link 36, 10 the construction being such that by adjusting the positions of the wing cams the position of the block 38 in the curved slot 40 of the crank arm 42 may be varied to vary the effective length of the arm 42 and thus to vary the amount of 15 tipping movement imparted to the roll 10 as the roll traverses the forepart and shank portions respectively of the shoe bottom.

In the course of the cycle of operations the pressure of the roll on the shoe is controlled 20 through a spring 64 (Fig. 1) by means including a cam wheel 66 fast on the cam shaft 30. The spring 64 is arranged to apply its pressure to a lever 68 which is pivoted at 70 on the frame of the machine and is connected by a link 72 to the 25 roll carrier 24. For controlling the spring 64 there is provided a lever arm 74 fast on a rockshaft 76 which has also fast thereon an arm 78 connected by a link 80 to a lever 82 pivoted at 84 on the frame of the machine and provided with 30 a roll 86 in engagement with the periphery of the cam wheel 66. The lever arm 74 is arranged to bear on ears 88 formed on opposite sides of a sleeve member 90 which is slidably movable in a holder 92 on the frame of the machine and 35 engages the upper end of the spring 64. The cam wheel 66 is so formed as to vary the pressure of the roll on the shoe in the same general relation to the cycle of relative movements of the leveling roll and the jack as heretofore. That is 40 to say, the cam wheel is provided with a cam 94 for applying the pressure first at the forepart of the shoe, with a depression 96 corresponding to the first relief of pressure at the ball line, a cam 98 for applying pressure while operating at 45 one side of the shank, a depression 100 corresponding to the relief of pressure in returning over the ball line, a cam 102 for applying the pressure in operating forwardly over the forepart at one side and in returning along the forepart 50 at the other side, a depression 104 corresponding to the first relief of the pressure at the ball line on that side, a cam 106 for applying the pressure in operating on the shank at that side, a depression 108 corresponding to relief of the pressure in 55 returning over the ball line, a cam 110 for applying pressure again at the forepart, and a final depression 112 corresponding to relief of the pressure as the roll leaves the shoe at the toe and also at the beginning of the cycle of operations 60 at the toe of the next shoe. It will be understood that the time in the cycle of the machine when the tipping of the roll takes place is controlled by the cam 54 and that the amount of tipping movement imparted to the roll by the cam 54 may be 65 varied by adjustment of the wing cams 56. Accordingly, each time in the cycle when the pressure of the roll is relieved the crank arm 42 is swung to impart to the roll its tipping movement so that when the pressure of the roll is again fully 70 applied to the shoe by the action of the cam wheel 66 that portion of the shoe which is being operated upon by the roll will be properly leveled.

For imparting to each jack its swinging movements there is provided power-operated mecha- 75

nism which is, for the most part, substantially the same as similar mechanism disclosed in Letters Patent of the United States No. 1,011,301, granted on December 12, 1911, upon an application of mine. It will be understood that each jack is connected to its operating mechanism by a spring-operated pin 114 (Fig. 1) which is arranged to enter a recess in the jack and is carried by the upwardly extending arm 116 of a bell-crank lever fulcrumed on the shaft 20 and provided with a forwardly extending arm 118 having an arcuate slot 120 formed therein. Slidably mounted in the slot 120 is a block 122 which is connected by a link 124 to a block 126 slidably mounted in an arcuate slot 128 formed in an arm 130 which is fast to a rockshaft 132 mounted in the frame of the machine. Between its ends the link 124 is pivotally connected to a supporting arm 134 connected to the frame of the machine. It will be understood that the link 124 is connected to mechanism for swinging it about its pivotal connection to the arm 134 in response to the movement of the heel post 14 toward or from the toe post 12 to vary the effective lengths of the arms 118, 130 and thus to vary the extent of swinging movement imparted to the jack in accordance with variations in the size adjustment of the jack. Fast to the rock-shaft 132 is an arm 136 which is connected by means of a link 138 to an arm 140 pivotally connected at 142 to the machine frame. Pivotally connected to the upper end of the arm 140 is a bell-crank lever 144 having an upwardly extending arm 146 carrying a roll 148 arranged to engage the cam 26, and a rearwardly extending arm 150 connected by a link 152 to one arm of a lever 154 loosely mounted on a shaft 156 supported by suitable bearings in the frame of the machine. The lever 154 has a forwardly extending arm 158 (Fig. 3) located between bosses 160, 162 on the lower ends of links 164, 166 respectively. The links 164, 166 are pivotally connected at their upper ends to blocks, one of which is shown at 168 (Fig. 1), each block being slidably mounted in a dovetailed arcuate slot 172. The slots 172 are formed respectively in arms 176, 178 (Fig. 2) which are pivotally mounted on the frame of the machine for swinging movements about a common axis 180. The arms 176, 178 are provided, respectively, with upwardly extending portions 182, 184 carrying cam rolls 186, 188 arranged to engage cam paths 190, 192 formed respectively in the opposite side faces of a cam wheel 194, fast to the cam shaft 30 (Figs. 2 and 4). Slidably mounted in a transverse recess in the forward end of the arm 158 of the lever 154 (Fig. 3) is a coupling pin 198 which may be moved longitudinally to engage alternately the boss 160 on the lower end of the link 164 in a recess 200 in the boss and the boss 162 on the lower end of the link 166 in a recess 202 in the boss, the lower end of each link 164, 166 being connected to the shaft 156 by a link 204 for movement on an arc concentric with the arc of movement of the pin 198. For moving the pin 198 into engagement either with the boss 160 in the recess 200 to connect the cam 190 through the arm 176 and link 164 to the lever 154 or with the boss 162 in the recess 202 to connect the cam 192 through the arm 178 and link 166 to the lever 154 there is provided mechanism which is substantially the same as that shown in the above-mentioned Letters Patent No. 1,011,301, this mechanism being controlled by a cam path 206 formed in the cam wheel 194 (Fig. 2).

Pivots connected to each link 164, 166 is a link 208 (Fig. 1) which extends forwardly and is pivotally connected to a block 210 at the front of the machine. Extending through each block 210 is a threaded adjusting rod 212 which is rotatably mounted in a casing 214 supported by the frame of the machine and is held against lengthwise movement in the casing by collars 216 fast to the rod 212. Each rod has its end portion formed to receive a wrench or crank by means of which the rod may be rotated to impart lengthwise movement to the block 210. It will be evident that by rotating the rods 212 the links 164, 166 may be swung about their pivotal connections to the links 204 to vary the positions of the blocks 168 in the arcuate slots 172 in the arms 176, 178 and thereby to vary the effective lengths of these arms.

It will be understood that the rearward and forward swinging movements above described are imparted to the jack by the cam 26 to cause the roll 10 to traverse the forepart and shank portions of the bottom of the shoe and that the extent of these movements may be varied by varying the size adjustment of the jack. It will also be understood that the time or times in the cycle when the pressure relief occurs are determined precisely by the shape of the cam wheel 66. The number of relative movements of the jack and leveling roll in directions lengthwise of the shoe are indicated diagrammatically in Fig. 5 by a line 218. This line indicates by its lateral separations the direction of tipping movement imparted to the roll in operating along the forepart and shank portions of the shoe first at one side and then at the other side of the shoe bottom. The machine as thus far described is substantially as shown in the previously mentioned prior Letters Patent.

For purposes of this invention the cams 190, 192 are so shaped as to impart to the bell-crank lever 144 through the arms 176, 178, adjustable links 164, 166, lever 154 and link 152 swinging movements in time relation to the swinging of the arm 140 by the cam 26 the extent of which may be varied by adjustment of the links 164, 166 to vary the rate of relative movement of the jack and roll 10 and thereby to control their relative positions at each time in the cycle when the pressure of the roll is relieved. By thus shaping the cams 190, 192 the relative positions of the shoe and roll when the pressure is relieved may be precisely determined in operating on shoes of different styles in each swinging movement of the jack instead of as heretofore only after the jack has completed its rearward swinging movement in each half of the cycle of operations of the machine. In operating upon shoes, for example, having a pronounced line or ridge across the sole at the ball of the shoe, such control of the shoe obviates any danger that there may otherwise be of the pressure of the roll obliterating this line or ridge. Moreover, since the roll 10 is usually tipped at one inclination to the bottom of the shoe when operating along the forepart and at one or more different inclinations to the shoe bottom when operating in the shank, by controlling the relative positions of the shoe and roll to cause the relief of pressure to occur each time when the roll is located at the junction of the shank and forepart, at which time the roll is tipped relatively to the shoe for operating either in the shank or along the forepart depending upon the direction of swinging movement of the shoe support relatively to the roll, not only

will all portions of the forepart and shank be properly leveled but there will be a tendency for the leveling roll to accentuate such a line or ridge on the sole at the ball of the shoe. It will be understood that during the first half of the cycle the coupling pin 198 (Fig. 3) is in engagement with the link 164 which is adjustably connected to the arm 176 controlled by the cam 190, and that during the last half of the cycle the coupling pin is in engagement with the link 166 adjustably connected to the arm 178 which is controlled by the cam 192, thus permitting the links 164, 166 to be adjusted independently of each other to vary the rate of movement of the shoe support to take care of variations in the length of the forepart and shank portions at the opposite sides of the shoe bottom. The shape of the cam 190 (Fig. 4) is such that as the arm 140 is swung by the cam 26 in a counterclockwise direction (Fig. 1) to impart to the jack its rearward swinging movement to cause the roll 10 to traverse the bottom of the shoe from the toe end to the heel breast line, the bell-crank lever 144 is ordinarily swung relatively to the arm 140 first in a counterclockwise direction and then to the same extent in a clockwise direction. The shape of the cam 26 is such as to accommodate shoes of a style having the longest forepart and shortest shank portion on which the machine is intended to operate. Accordingly, in operating upon shoes of other styles such counterclockwise swinging movement of the bell-crank lever 144 relatively to the arm 140, the amount of which is determined by adjustment of the links 164, 166, causes the jack to be swung rearwardly at a lower rate of speed than if the bell-crank lever 144 had been held in fixed relation to the arm 140. Such counterclockwise swinging movement is imparted to the bell-crank lever 144 until the time when the roll 86 engages the cam 66 in the depression 96 to relieve the pressure of the leveling roll 10 on the bottom of the shoe. At this time the roll 188 is at the point *a* in the cam path 190 (Fig. 4). Thereafter as the jack continues to swing rearwardly the bell-crank lever 144 is swung relatively to the arm 140 in a clockwise direction to cause the jack to be swung at a greater rate of speed, the shape of the cam 190 being such that the bell-crank lever 144 is returned to its initial position substantially at the time when the roll 10 reaches the heel breast line. As the jack is then swung forwardly and rearwardly to cause the roll 10 to operate in the shank portion of the shoe the bell-crank lever 144 is swung relatively to the arm 140 first in a counterclockwise direction and then in a clockwise direction in time relation to the swinging movements of the arm 140, thus increasing the rate of speed of the jack, after which, as the jack is swung forwardly by the arm 140 to return the roll to the toe end of the shoe, the bell-crank lever 144 is swung in a counterclockwise direction to increase the rate of speed of the jack until the time of the relief of pressure of the leveling roll 10 by the engagement of the roll 86 with the cam 66 in the depression 100. At this time the roll 188 is at the point *b* in the cam path 190 (Fig. 4). Thereafter the bell-crank lever 144 is swung in a clockwise direction relatively to the arm 140 in its initial position substantially at the time when the roll 10 reaches the toe end, thus causing the jack to be swung at a lower rate of speed as the roll traverses the shoe bottom from the ball line forwardly to the toe end. It will be understood that swing-

ing movements in time relation to the swinging of the arm 140 similar to those above-described are imparted to the bell-crank lever 144 by the cam 192 as the leveling roll 10 is operating along the opposite side of the forepart and shank portions of the shoe bottom in the last half of the cycle of operations of the machine. It will also be understood that by adjusting the positions of the links 164, 166 to vary the effective lengths of the arms 176, 178, swinging movements of greater or less extent may be imparted to the bell-crank lever 144 to vary the rate of relative movement of the jack and leveling roll in operating upon shoes of different styles. From the above description it will be evident that since the direction of swinging movement imparted to the bell-crank lever 144 is changed each time in the cycle when the pressure of the leveling roll 10 is relieved in traversing the ball line, by varying the extent of swinging movement imparted to the bell-crank lever 144 to vary the rate of relative movement of the jack and leveling roll when the roll is traversing both the forepart and shank portions, the time when the pressure relief of the leveling roll takes place may divide the entire length of swinging movement of the jack into two movements of any desired ratio. In operating upon shoes of different styles, that is, shoes that differ in respect to the relative lengths of their forepart and shank portions, the relative positions of the jack and leveling roll may be thus controlled to position each shoe with its ball line under the roll 10 at each time when the pressure of the roll is relieved. It will be evident that since the bell-crank lever 144 is returned to its initial position at the end of each rearward and each forward swinging movement of the jack to cause the roll to traverse the shoe bottom from the toe end to the heel breast line and from the heel breast line to the toe end, the rate of relative movement of the jack and roll may thus be varied to determine adjustably the position of the jack relatively to the roll at each time when the pressure of the roll on the shoe is relieved without varying the entire length of swinging movement imparted to the jack which may be varied as heretofore to accommodate shoes of different sizes by varying the size adjustment of the jack. The relative timing of the cams for operating the shoe support and the leveling roll is illustrated diagrammatically in Fig. 6.

Having described the invention, what I claim as new and desire to secure by Letters Patent of the United States is:

1. A leveling machine having, in combination, a shoe support, a leveling roll, means for effecting relative movement of said shoe support and leveling roll in directions lengthwise of the shoe to cause the leveling roll to operate along the bottom of the shoe, means for pressing the roll upon the shoe and for relieving the pressure at predetermined times in the cycle of operations of the machine, and means for varying the rate of relative movement of the shoe support and leveling roll in operating upon both the forepart and shank to control their relative positions at each and every time in the cycle when the pressure of the roll is relieved in operating on shoes of different styles.
2. A leveling machine having, in combination, a leveling roll, a shoe support mounted to swing rearwardly and forwardly beneath said leveling roll to cause the roll to operate along the bottom of a shoe on said support, means for pressing

- the roll upon the shoe and for relieving the pressure at predetermined times in each cycle of operations of the machine, means for imparting to the shoe support its rearward and forward swinging movements, and cam means arranged to act through said last-named means to control variably the relative positions of the shoe support and the roll at each and every time in the cycle of the machine when the pressure of the roll is relieved.
3. A leveling machine having, in combination, a leveling roll, a shoe support mounted to swing rearwardly and forwardly beneath said leveling roll to cause the roll to operate along the bottom of a shoe on said support, means for pressing the roll upon the shoe and for relieving the pressure at predetermined times in each cycle of operations of the machine, means for imparting to the shoe support its rearward and forward swinging movements, and means for adjustably varying the rate of movement of the shoe support when the roll is traversing both the forepart and shank portions of the shoe bottom to cause the relief of pressure to occur when the roll is located substantially at the junction of the forepart and shank in operating on shoes of different styles.
4. A leveling machine having, in combination, a shoe support, a leveling roll, means for effecting relative movement of said shoe support and leveling roll in directions lengthwise of the shoe to cause the leveling roll to operate along the bottom of the forepart and shank portions of the shoe, means for imparting to the roll tipping movements laterally of the shoe at predetermined times in the cycle of operations of the machine, and means for adjustably varying the rate of relative movement of the shoe support and leveling roll when the roll is traversing both the forepart and shank portions of the shoe bottom to cause the tipping of the roll to occur when the roll is located substantially at the junction of the forepart and shank in operating upon shoes of different styles.
5. A leveling machine having, in combination, a leveling roll, a shoe support having heel and toe posts relatively adjustable to accommodate shoes of different sizes, means for effecting relative movement of said shoe support and leveling roll in directions lengthwise of the shoe to cause said leveling roll to operate along the bottom of the shoe, said last-named means being constructed to vary the entire extent of said relative movement in accordance with variations in the relative positions of the heel and toe posts, means for pressing the roll upon the shoe and for relieving the pressure at predetermined times in the cycle of operations of the machine, and means for adjustably varying the rate of relative movement of the shoe support and leveling roll in operating upon both the forepart and shank to control their relative positions each and every time in the cycle when the pressure of the roll is relieved in operating upon shoes of different styles without varying the entire extent of relative movement of the shoe support and leveling roll lengthwise of the shoe.
6. A leveling machine having, in combination, a leveling roll, a shoe support mounted to swing rearwardly and forwardly beneath said leveling roll to cause the roll to operate along the forepart and shank portions of the bottom of a shoe on said support, means for pressing the roll upon the shoe and also for relieving the pressure at each time in the movement of the shoe support
- when the roll is at the junction of the forepart and shank portions of the shoe bottom, means for imparting to the shoe support its rearward and forward swinging movements, and means for adjustably varying the rate of movement of the shoe support when the roll is traversing both the forepart and shank portions of the shoe to vary the amount of the relative movement of the roll and support prior to each relief of pressure of the roll in accordance with variations in the lengths of the forepart and shank portions of shoes of different styles.
7. A leveling machine having, in combination, a leveling roll, a shoe support mounted to swing rearwardly and forwardly beneath said leveling roll to cause the roll to operate along the bottom of a shoe on said support, means for pressing the roll upon the shoe and also for relieving the pressure at predetermined times in the cycle of operations of the machine, means acting in time relation to said last-named means for imparting to said roll tipping movements of different extent laterally of the shoe to cause the roll to operate along the opposite sides of the shoe bottom, means for imparting to the shoe support its rearward and forward swinging movements, and different mechanisms arranged to act alternately through said last-named means to determine the rate of movement of the shoe support when the roll is traversing both the forepart and shank portions at the opposite sides of the shoe bottom to cause the relief of pressure to occur when the roll is located at the junction of the forepart and shank, said mechanisms being adjustable independently of each other to vary the rate of movement of the shoe support to take care of variations in the lengths of the forepart and shank portions at the opposite sides of the shoe bottom.
8. A leveling machine having, in combination, a leveling roll, a shoe support mounted to swing rearwardly and forwardly beneath said leveling roll to cause the roll to operate along the bottom of the forepart and shank portions of a shoe on said support, a cam, connections between said cam and said shoe support for imparting to said support its swinging movements including a pivoted arm arranged to be swung in one direction by said cam to impart to said support its rearward swinging movement and to be swung in the opposite direction to impart to said support its forward swinging movement, means operating in time relation to the swinging movements of said arm for pressing the leveling roll upon the shoe and also for relieving the pressure of the roll on the shoe, and mechanism operating in time relation to said last-named means for imparting to said pivoted arm independently of said cam swinging movements of variable extent in opposite directions to vary the rate of swinging movement imparted to said shoe support when the roll is traversing both the forepart and shank portions of the shoe to control the relative positions of the shoe support and roll each and every time when the pressure of the roll is relieved in operating upon shoes of different styles.
9. A leveling machine having, in combination, a leveling roll, a shoe support mounted to swing rearwardly and forwardly beneath said leveling roll to cause the roll to operate along the bottom of the forepart and shank portions of a shoe on said support, a cam, connections between said cam and said shoe support for imparting to said support its swinging movements including a pivoted arm arranged to be swung in one direction by said cam to impart to said support its rear-

ward swinging movement and to be swung in the opposite direction to impart to said support its forward swinging movement, means operating in time relation to the swinging movements of said arm for pressing the leveling roll upon the shoe and for relieving the pressure of the roll on the shoe, and mechanism for adjustably varying the rate of swinging movement imparted to said pivoted arm by said cam without varying the extent of its swinging movement to vary the rate of

swinging movement imparted to said shoe support when the roll is traversing both the forepart and shank portions and thereby to vary the extent of swinging movement imparted to the shoe support before each relief of pressure of the roll occurs in accordance with variations in the lengths of the forepart and shank portions of shoes of different styles. 5
